METHOD OF FORMING PAPER ROLLS

Louis A. Straubel, Green Bay, Wis.

Application November 14, 1934, Serial No. 752,971

6 Claims. (Cl. 164—17)

The invention relates to an article of manufacture and method of forming the same. More particularly it relates to compact rolls of relatively soft paper such as toilet paper, divided transversely to provide sections connected only at one marginal edge by narrow ties, and also to a method of forming such rolls.

Rolls of paper of the kind described are well known in the art and heretofore such rolls have been formed by winding a sheet of paper of the width of the roll, which has been perforated or partially severed along longitudinally spaced transverse lines. The sheet is thereby adapted to be completely detached at such lines upon unwinding the roll and exerting a pull upon the paper. The lines of partial severance heretofore provided for such sheets consist of rows of perforations or relatively short slits so formed as to leave the marginal edges of the sheet either unsevered or only slightly severed in order that there be no corners folded under when winding the sheet into a roll. There must also be sufficient unsevered material at such lines to withstand the pull necessarily exerted upon the sheet when forming it into a roll. The rolls so formed are adapted to be mounted in such a manner that they are comparatively easily unwound and as a result the sections are not severed by the slight pull necessary for unwinding the roll. Furthermore, unless care is exercised by the user, a plurality of sections are unwound at each operation and substantial and unnecessary lengths of paper are detached with the result that a considerable portion of each roll is wasted.

It is one of the objects of the invention to provide individual rolls of paper comprising longitudinal sections of practical length connected only at one marginal edge by ties which are easily severed by the pull normally necessary to unwind the roll, whereby the waste, which is incidental to the use of rolls not so completely severed, is avoided.

The invention also contemplates economy in manufacture of individual rolls by forming a multiple roll from a sheet of paper wide enough to provide a plurality of rolls, the sheet having been cut by means of a die stamp or otherwise to form therein a plurality of transverse slits arranged in as many longitudinal rows as there are individual rolls to be formed from the sheet. The slits in each row are of a length slightly less than the width of the individual rolls to be formed, and are so arranged that the sheet retains sufficient tensile strength to be wound into a compact multiple roll without tearing. All or some of the slits

comprising each row terminate in imaginary parallel rectilinear longitudinal lines forming common boundaries for adjacent rows and for the outer edges of the border rows. The multiple roll is then formed into a plurality of individual rolls of the desired width by cutting the roll transversely at sections coincident with said longitudinal boundary lines with the result that each individual roll comprises a plurality of sections fastened to the next adjacent sections by narrow ties.

It is another object of the invention to provide a multiple roll of paper from a single sheet slit transversely in such a manner that upon cutting the roll at selected sections to form individual rolls, said individual rolls will each comprise a relatively narrow sheet of paper divided transversely to provide a plurality of longitudinally extending sections connected only by narrow ties.

Still another object of the invention is the provision of a novel method of forming a relatively wide blank sheet of paper into a plurality of individual compact rolls each comprising a narrow sheet of paper having the same length as the blank and completely severed transversely other than by a narrow tie at a plurality of longitudinally spaced apart transverse lines.

Another object of the invention is the provision of a novel method of providing a compact roll comprising a narrow sheet of soft easily torn paper divided into a plurality of longitudinal sections each connected to the adjacent sections by a single narrow tie.

A still further object of the invention is the provision of a novel method of forming toilet paper rolls which results in economy both in the production and in the use of the rolls.

Many other objects and advantages of the construction herein shown and described will be obvious to those skilled in the art from the disclosure herein given.

To this end my invention consists in the novel method herein described and also in the construction, arrangement and combination of parts herein described and shown and more particularly pointed out in the claims.

In the drawings wherein like reference characters indicate like or corresponding parts,

Fig. 1 is a view of a multiple roll formed from a sheet of paper slit transversely in accordance with the principles of the invention;

Fig. 2 is a view of still another multiple roll similar to, but providing a different arrangement of slits than those shown in Fig. 1;

Fig. 3 is a view of either of the rolls shown in

Figs. 1 and 2 with the roll enclosed by a close-fitting continuous wrapper;

Fig. 4 is a diagrammatic view of a device operable to cut the multiple rolls transversely into a plurality of individual rolls; and

Fig. 5 is a view of a typical individual roll adapted to be formed by cutting the multiple roll, the individual roll being shown as it appears when partially unwound.

10 Referring now more particularly to Fig. 1 of the drawings, the numeral 10 designates a partially unwound, multiple roll formed from a sheet of paper 11. The sheet 11, preliminary to winding it into multiple rolls is provided with a plurality of transversely extending slits 12 formed in any suitable manner such as by a die cutter or the like. The slits 12 are arranged in longitudinally extending rows separated by common imaginary rectilinear parallel boundary lines indicated by dotted lines 13 with the outer edges of each of the border rows of slits bounded by imaginary lines indicated by dotted lines 14 parallel to the lines 13 and closely spaced to the adjacent marginal edges of the sheet.

25 The slits 12 comprising each row are staggered relative to the slits comprising adjacent rows with alternate ones of the slits comprising each row terminating in the same boundary line and the remaining slits terminating in the opposite boundary line. A sheet of thin easily torn paper, such as toilet paper having slits arranged as described, provides sufficient tensile strength to adapt it to be wound into a compact multiple roll without tearing. The multiple roll 10 formed 30 from the sheet 11 after being slit as described is enclosed, as shown in Fig. 4, by a continuous wrapper 24 having marker lines 25 on its outer surface so spaced as to overlie the longitudinal lines 13 and 14 forming the boundary lines of the rows of slits 12. Any suitable indicia, such as a trade-mark or trade-name, or manufacturer's name, generally designated by the letter "K", may be provided on the wrapper 24 between the lines 25. The lines 25 are provided on the 35 wrapper to indicate the sections at which the multiple roll is designed to be cut transversely to provide individual rolls of the usual width. Obviously the cutting of the multiple roll at the sections designated will sever the sheet 11 along the longitudinal lines 13 and 14 and will thereby cut 40 across and open each of the slits 12 at one end.

The longitudinal sections of the sheet 11 resulting from the described cutting of the multiple roll, each consists of a plurality of short sections connected with the adjacent sections at the lines of slit only by a tie having a width equal to the difference between the length of the slits 12 and the width of the individual rolls. Each individual roll thus consists of a narrow sheet of 45

50 paper severed transversely except for a narrow tie at a plurality of points in such a manner that the sheet could not be wound into a roll.

Another embodiment of the invention is shown in Fig. 2 as comprising a multiple roll 20, formed 55 from a sheet 21 providing a plurality of transversely extending slits 12. The slits 12 are arranged in a plurality of longitudinally extending rows with the slits in each row staggered relative to the slits in adjacent rows. The longitudinal rows of slits, except one border row and its next adjoining row, are separated from the next adjacent row by an imaginary rectilinear line 22, said border row and next adjacent row line 22, having a common imaginary boundary line 23 60 parallel to the lines 22. The outer ends of the

slits comprising the border rows terminate short of the edges of the sheet 21 and have their other ends respectively terminating in the lines 22 and 23. The slits 12 comprising each intermediate row all terminate in a single imaginary boundary line with the opposite ends stopping short of the imaginary boundary line in which the slits of the next adjacent row terminate. The roll 20 is adapted to be enclosed with a wrapper similar to the wrapper 24 shown in Fig. 4 but differing 10 therefrom by omitting the end marker lines 25, it being understood that the ends of the wrapper coincide with the marginal edges of the sheet and that the lines 25 respectively overlie the lines 22 and 23 forming the boundaries of the intermediate rows of slits in the sheet 21.

The multiple rolls 20, described as formed from the sheets 21, are also adapted to be cut transversely at planes indicated by the marking lines 25 formed on the wrapper 24, and in so cutting 20 the rolls, the sheets comprising the same will be cut along the boundary lines separating the various rows of slits and thereby intersect one end of each transverse slit 12 with the result that the individual rolls each comprise a narrow sheet of 25 paper consisting of a plurality of sections connected to the next adjacent sections only by narrow marginal ties.

The multiple rolls 10 and 20 may be cut as described by using any suitable tool but because 30 of the soft and yielding qualities of the paper usually used in such rolls, such cutting is most satisfactorily accomplished by positioning the rolls in a close fitting container whereby they are held firmly on both sides of the cutting sections. A typical device adapted for cutting such rolls is shown in Fig. 4 as comprising a shaft 28 having a plurality of cutting discs 29 mounted thereon in spaced relation corresponding to the spacing of the lines 25 on the wrapper sheets 24. 35 The container for the rolls is shown as comprising a plurality of aligned closely spaced cylindrical members 31 fixedly mounted on a shaft 30. The shaft 30, carrying the members 31, is adapted to be moved towards and away from the shaft 28 40 by any suitable means such as a rack, not shown. The shaft 28, carrying the cutting discs 29, is adapted to be rotated by any suitable means with the discs in operative engagement with a roll mounted in the members 31. The spacing of the 45 members 31 is such as to permit entrance of the discs 29 as the multiple roll is moved towards the rotating discs and the multiple roll is thereby sheared or cut into individual rolls having smooth ends and similar wrappers. Further description 50 of the structure and operation of the typical device for cutting the multiple rolls is omitted since it is not claimed as forming any part of the invention.

Fig. 5 illustrates a typical individual roll 60 formed in the manner hereinbefore described and designated by the numeral 33 as it appears with the wrapper section 24 removed, and the roll partially unwound. The narrow sheet comprising the roll is divided into longitudinal sections 65 34 connected by single marginal ties 35.

The roll 33 is identical with the individual rolls that are to be formed by practicing the method as described and shown for the sheet shown in Fig. 1. An individual roll formed from the sheet 70 shown in Fig. 2 differs from the roll 33 only in having all of the ties on the same edge of the roll.

Thus it will be seen that I have provided compact rolls of toilet paper or the like substantially severed transversely at a plurality of lines to 75

promote economy in use, the severance being sufficiently complete that the roll could not be formed from a sheet so severed and that I have also provided a novel method of forming such rolls which results in economy of manufacture.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. The method of forming a blank sheet of paper into a plurality of individual rolls, which consists in forming as many longitudinal rows of transversely extending slits in the blank as there are rolls to be formed, with adjacent rows having a common rectilinear longitudinal boundary line, the spacing of said lines being greater than the length of the slits arranged in longitudinal rows therebetween, one end of each slit stopping short of a boundary line and the other end terminating in the opposite boundary line, then forming a roll of said sheet, and then cutting said roll at sections corresponding to said longitudinal lines.

2. The method of forming a blank sheet of paper into a plurality of individual rolls which consists in forming as many longitudinal rows of transverse slits in the blank as there are rolls to be formed, with adjacent rows having a common rectilinear boundary line, the spacing of said lines being greater than the length of the slits, alternate ones of said slits in each row terminating in one longitudinal boundary line and the remainder of said slits in each row terminating in an adjacent longitudinal boundary line, then forming said sheet into a roll, and then cutting said roll at sections corresponding to said longitudinal lines.

3. The method of forming a blank sheet of paper into a plurality of individual rolls which consists in forming as many longitudinal rows of transverse slits in the blank as there are rolls to be formed, the length of said slits being less than the width of the individual rolls to be formed, the slits in each row except one marginal row all having one end terminating in a longitudinal line in spaced relation to the adjacent

ends of the slits forming the next adjacent row, said marginal row having its slits terminating in the same longitudinal line as the next adjacent row, then forming said sheet into a roll, and then cutting said roll at sections corresponding to said longitudinal lines.

4. The method of forming a blank sheet of paper into a plurality of individual rolls which consists in forming as many longitudinal rows of transverse slits in the blank as there are rolls to be formed, with the slits in each row terminating in a rectilinear longitudinal line, the spacing of said lines being greater than the length of said slits, the slits comprising the marginal rows having their outer ends stopping short of the edge of the sheet, the slits in one marginal row and in the next adjacent row terminating in the same longitudinal line, then forming a roll of said sheet, and then cutting said roll at sections corresponding to said longitudinal lines.

5. The method of forming a plurality of rolls from a single blank sheet of paper which consists in forming a plurality of transverse slits in the blank arranged in as many longitudinal rows as there are rolls to be formed, then forming the sheet so slit into a cylindrical roll, then cutting said roll transversely to its longitudinal axis at planes corresponding to selected lines between said rows whereby individual rolls are formed respectively containing a row of slits, the slits so formed in each roll having a length less than the roll in which it is formed with each slit having one terminus in a cutting plane.

6. The method of forming a plurality of rolls from a single blank sheet of paper which consists in forming a plurality of transverse slits in the blank arranged in as many longitudinal rows as there are rolls to be formed, then forming the sheet so slit into a cylindrical roll, then cutting said roll transversely to its longitudinal axis at planes corresponding to selected lines between said rows whereby individual rolls are formed respectively containing a row of slits, the slits so formed in each roll having a length less than the roll in which it is formed, certain of the slits in each row having one end terminating in exact accordance with one cutting plane forming a boundary for its roll and others of said slits in each row having their opposite ends terminating in the cutting plane forming the other boundary of its roll.

LOUIS A. STRAUBEL.
